UNITED STATES PATENT OFFICE.

EDWARD O'SULLIVAN, OF SAN FRANCISCO, CALIFORNIA.

EMERGENCY-CISTERNS FOR FIRE-ENGINES.

No. 901,733.

Specification of Letters Patent.

Patented Oct. 20, 1908.

Application filed November 17, 1906. Serial No. 343,802.

To all whom it may concern:

Be it known that I, EDWARD O'SULLIVAN, a citizen of the United States, residing in the city and county of San Francisco and State of California, have invented new and useful Improvements in Emergency-Cisterns for Fire-Engines, of which the following is a specification.

This invention has for its object to provide a storage-cistern or reserve-supply of water from which a fire-engine may draw in an emergency, in the event of accident to the hydrant or the street-main.

The invention is designed to be an auxiliary to the street hydrant or fire-plug; and in addition thereto it is designed to furnish a temporary supply of water to the neighborhood for household purposes, when the local water-supply is cut off for the time by injury to the mains or water-pipes.

To these ends and objects chiefly my said invention comprises certain novel parts and combination of parts, producing what I have termed an emergency-cistern, as an auxiliary to the water-supply system of a city for the use of the fire department, as hereinafter described and pointed out in the claims at the end of this specification.

The following description explains at length the nature of my said invention, and the manner in which I proceed to construct, produce and carry out the same; reference being had to the accompanying drawings.

Figure 1 of the drawings is a sectional view of a cistern embodying my invention, showing the cistern located under a street or roadway, and having a permanent connection with the water-main for filling it with water. The parts are shown generally in section, with the exception of the suction-pipes and the suction-hose of the engine—which is attached to one of the pipes—and the hand-pump that is provided for drawing water from the cistern for washing or drinking purposes. Fig. 2 is a vertical longitudinal section on an enlarged scale of the upper portion of the cistern, showing connections for the suction-hose of two engines with the same coupled for use, and the hand-pump set in position for use. Fig. 3 is a vertical cross section through the coupling chamber of the cistern. Fig. 4 is a plan or top view of Fig. 1. Figs. 5 and 6 are top views of coupling-chambers having connections for three and four engines, respectively.

The covers that close the chamber are omitted in Fig. 5; but are indicated in Fig. 6.

The various parts of the structure are designated herein as the storage-chamber *a*, the coupling-chamber *b*, the suction-pipes *d*, the hand-pump *f*, and the water-supply pipe *g*, connecting the storage-chamber with the street-main.

The storage-chamber *a* is formed by cementing, or otherwise finishing the walls and the bottom of an excavation in the street or roadway in a suitable manner to render the same water-tight, where the character of the soil or other conditions may require it. Or the chamber can be formed by sinking a water-tight tank in the ground to a proper depth to bring the top below the surface of the street. In the top of this chamber when it is so formed or built in the ground a circular casting having a flat bottom 2 and a standing-rim 3 is permanently set and fixed in masonry or concrete, with the top of its rim a little below the level of the surface. The space inclosed by the standing-rim forms a chamber *b* to contain and inclose the coupling-ends of the suction-pipes, the hand-pumps, and the other parts and connections.

A removable cover composed preferably of two parts or sections 12 hinged together at 13 closes the top of the coupling-chamber. A beam or supporting bridge-piece 14 held at the ends in sockets 15 on the rim 3 and extending diametrically across the top of the chamber supports the cover along the line of the hinges. Additional supports of the same character can be provided when the size of the covers may require support at other parts.

It is considered better to have the covers and the supports removable, and not permanently attached to the top of the chamber.

The plate 2 is provided with a central opening 2' that is closed by a plate 2'' removably secured to the top by bolts. The suction pipes *d* are secured to and extend through the plate 2'' and are each provided with an angular extension above the top-plate turning outwardly or towards the rim 3, in line with an inclined groove or depression *m* extending in a radial line from the chamber in the surface of the street, or in the pavement adjacent to the standing-rim of the chamber. At such point the standing-rim 3 is cut down in line with the depressed portion, so that the suction-hose *X* of the en-

- gine when coupled to the suction-pipe will extend in a straight line from the angular bend of the suction pipe and at a proper angle to be connected to the engine. The 5 inclined depressions *m* are closed by extensions 17 provided on the cover for that purpose. These extensions 17 may be composed of separate pieces, or they may be permanent parts of the covers.
- 10 On the end of each suction-pipe *d* is a coupling 6 and also a hand-valve 20 of any well-known construction; each pipe being thus provided with a valve for turning on or shutting off the supply at will separately 15 of the others. Usually, all the suction-pipes *d* are carried into and attached to a single strainer *p* at the bottom, of the cistern, as seen in Fig. 1.
- Separate connections for more than two 20 engines are provided by arranging the suction-pipes as illustrated in Figs. 5 and 6, where three suction-pipes are seen in one, and four in the other.
- A small hand-pump *f* is mounted on the 25 bottom-plate 2 and is connected by a small service-pipe 23 with the supply of water below; the end of the pipe 23 being fixed in the strainer box *p*. This pump furnishes a convenient means for drawing water from the 30 cistern in small quantities for household use in the event of an accident to the street-main whereby the house supply is temporarily cut off.
- The pump-barrel is made in two sections 35 separable horizontally, and the two sections are connected by a hinge whereby the upper section may be turned down and stowed away below the top of the coupling-chamber without removing the pump.
- 40 The adjacent ends of the two sections of the pump-barrel are adapted to fit together and form a water-tight joint when the pump is set up for use. A catch 26 is provided on the base for holding the two sections in place 45 when set up.
- The stationary supply-pipe by which the cistern is filled from the street-main is pro-

vided with a hand-valve *h* the stem of which is carried upward through the bottom-plate 2 and is fitted with a hand-wheel for readily 50 operating the valve from the coupling-chamber.

Having thus described my invention, I claim—

1. In a cistern, the combination with the 55 water reservoir, a top for closing the said reservoir, a coupling chamber above the top, a cover for closing the said coupling chamber, a suction pipe, a branch pipe leading from the coupling chamber to a point below 60 the water in the reservoir, means for connecting the suction pipe with an engine hose or the like, and a foldable pump connected to the branch pipe arranged to be folded down when the said cover is closed, substantially 65 as set forth.

2. In a cistern, the combination of a water reservoir, a coupling chamber provided with a depressed portion extending outwardly therefrom, a suction pipe extending from a 70 point below the water in the reservoir to the coupling chamber, the said pipe being bent at its upper end so as to lie in a line substantially parallel with the plane of the depressed portion, a cover for closing the top 75 of the coupling chamber, and a wing on the said cover for closing the said depressed portion, substantially as set forth.

3. In a cistern, the combination of a water reservoir, a coupling chamber, provided with 80 a depressed portion extending outwardly therefrom, and a suction pipe extending from a point below the water in the reservoir to the coupling chamber, the said pipe being bent at its upper end so as to lie in a line substantially parallel with the plane of the depressed portion, substantially as set forth. 85

In testimony whereof I have signed my name to this specification in the presence of two subscribing witnesses.

EDWARD O'SULLIVAN.
